UNITED STATES PATENT OFFICE.

CHARLES G. TAYLOR, OF LOS ANGELES, CALIFORNIA.

LOCK.

1,136,735.

Specification of Letters Patent.

Patented Apr. 20, 1915.

Application filed December 26, 1914. Serial No. 879,084.

To all whom it may concern:

Be it known that I, CHARLES G. TAYLOR, a citizen of the United States, residing at Los Angeles, in the county of Los Angeles 5 and State of California, have invented certain new and useful Improvements in Locks, of which the following is a specification.

This invention relates to improvements in locks, and it is an object of the invention to 10 provide a simple inexpensive lock which is provided with an interior locking means adapted to be shifted by certain movements for locking and unlocking the shackle portions of the lock.

It is also an object of the invention to 15 provide a lock with coöperating shackle portions and an interior shifting tumbler adapted to be moved in accordance with the position of the lock for controlling the action of said shackle portions.

It is a further object of the invention to 20 provide a lock with shackle controlling members in which a gravity actuated member within the lock structure is employed to lock 25 and unlock the shackle portion of the device.

With these and other objects in view the 30 invention comprises certain novel constructions, combinations and arrangements of parts as will be hereinafter fully described and claimed.

In the accompanying drawing: Figure 1 is a side elevation of a lock constructed in accordance with the present invention, a portion of one of the side plates being 35 broken away to reveal the inner parts of the lock. Fig. 2 is a side elevation of the lock turned in reversed position so that the tumbler will permit the opening of the lock shackle members. Fig. 3 is an edge elevation 40 of the lock locking at the shackle end thereof. Fig. 4 is a central longitudinal sectional view taken through the lock, with the shackle portions in locked position. Fig. 5 is a side elevation of one of the 45 shackle members with its controlling member or disk. Fig. 6 is a similar view of the other shackle member.

It is a purpose of the present invention to 50 provide a lock, usually of the padlock type which is a keyless lock and has separable shackle portions adapted to be brought together to form a complete shackle, the members or disks which carry the shackle member being controlled by a tumbler or disk 55 which may be shifted for locking or unlocking the said shackle portions without the use of a key.

The details and features of the invention will now be more specifically described with reference to the accompanying drawing in 60 which—

1 and 2 indicate coöperating shackle members, 3 and 4 disks carrying the same and 5 a tumbler or shifting member for locking the shackle members. 65

The members 3 and 4 are preferably flat disks or circular members adapted to be applied upon each other, though of course they may be made in other shapes if desired without departing from the spirit of the invention. The members 3 and 4 are pivotally connected at the center by a rivet or pivot bolt 6, so that they may turn upon each other. The shackle portions 1 and 2 usually project from the edges of the said 70 members 3 and 4 and are generally offset at 7 and 8 so that the greater portion of the said shackle members will lie in the same plane as will be clearly understood by reference to Fig. 3. 75

The ends of the shackle members 1 and 2 are preferably made with portions which lap upon and pass each other sufficiently to form a strong completed shackle when the said members are brought together. The 80 said ends are usually bifurcated at 9 and 10 and one portion turned in one direction and the other portion in the other direction to form a firm joint between the shackle members. The portion 11 is bent parallel with 85 the portion 12 upon the opposite shackle member so that they may lap in parallel position upon each other as shown in Fig. 3. The other portions 13 and 14 of the bifurcated shackle ends lap upon each other in 90 the other direction and thus extend diagonally across the portions 11 and 12 as shown in said Fig. 3. The shackle portions cannot be sprung in either direction with respect to 95 each other when formed in this way and afford a strong and complete shackle for the lock when in closed position. 100

In order to lock the shackle members the disks or members 3 and 4 are provided with openings or slots 15 and 16 which preferably extend radially with respect to the pivot 6 and which coincide or fit one over the other when the shackle members are closed, so that a tumbler member or disk 5, which is made of thicker material than 110 the members 3 and 4, may extend into both of the openings 15 and 16 and when occupying the lower portions thereof as shown in Figs. 1 and 4, will lock the said members 105

3 and 4 against movement upon the pivot pin 6. In order to be able to move the members 3 and 4 when it is desired to open the shackle members 1 and 2, the openings 5 or recesses 15 and 16 are provided with offset extensions 17 and 18 at their inner ends, but extending in opposite directions with respect to each other. It will thus be evident that when the tumbler 5 is brought to the inner ends of the openings or recesses 15 and 16, the members 3 and 4 may be turned upon their pivot to the extent permitted by the length of the offset recesses 17 and 18.

In using the lock when the shackle members 1 and 2 are brought together and the said lock is held so that the tumbler 5 will drop into the lower portion of the recess formed by the superposed openings 15 and 16, the members 3 and 4 will be locked and the shackle members 1 and 2 will be firmly held in their closed positions. When it is desired to open them, the lock must be turned into a sufficiently inverted position to permit the tumbler 5 to roll or drop to the inner ends of the openings 15 and 16, when as indicated in Fig. 2, the members 3 and 4 may be moved on the pivot 6 as the tumbler 5 will engage the offset recesses 17 and 18. The shackle members 1 and 2 may of course be pushed together when it is desired to secure an object or thing, at any time and by holding the lock in pendant position upon its shackle, the tumbler will drop again so as to lock the said shackle members. The openings or recesses in the members 3 and 4 must of course be closed to properly hold the tumbler 5, movably in place. The said recesses need not of course extend entirely through the material of the members 3 and 4 as will be evident, but side or cheek plates 19 and 20 are preferably used and applied upon the outer faces of the members 3 and 4 to provide walls for inclosing the said recesses 15 and 16 and their offset extensions 17 and 18. The said side plates are held in position by the heads of the rivet or pivot pin 6 thus becoming a permanent inclosing means for the said recesses and tumblers. The said plates may be welded or otherwise firmly fastened to the members 3 and 4 or may be only held in place by the heads of the rivet 6 as may be found desirable, all within the spirit and scope of the invention.

It will be apparent that the lock may be made in many sizes and may be made strong enough to be used in the place of any ordinary padlock. It is quickly and easily locked and unlocked and requires no key or member separate therefrom for accomplishing the locking and unlocking operation. The device may also be employed as a nov-

elty or puzzle, there being nothing upon the exterior of the lock to indicate in any way, how the shackle members are to be released and permitted to open. Thus only those who learn the secret of the lock can operate it and unlock the shackle.

What is claimed is:

1. A lock having separable shackle members and a gravity actuated tumbler adapted to be shifted by altering the position of the lock for locking or unlocking the said shackle members.

2. A lock comprising pivoted disks applied face to face and having radial recesses therein adapted to be brought into coincidence, a tumbler disk movable in said recesses for locking the disks against movement, the said recesses having offset extensions for receiving the tumbler when the parts are in unlocked position, and shackle members carried by said disks.

3. A lock comprising shackle carrying members mounted to revolve with respect to each other and having shackle arms projecting therefrom, the said arms having interlocking edge portions adapted to form a firm joint between the parts, the said members having angular recesses adapted to be brought into coincidence and a disk of sufficient thickness to extend into both recesses for locking the shackle arms.

4. A lock having a separable shackle, pivoted disks carrying the members of said shackle and having superposed recesses formed therein, said recesses having lateral extensions projecting in opposite directions with respect to each other from the inner ends of said recesses, and a loose tumbler engaging said recesses, the structure being such that when the tumbler is at the outer end of the said recesses the shackle members will be locked, and when the lock is inverted and the tumbler permitted to fall into the other ends of the recesses, the shackles will be permitted to open.

5. A lock having disks pivoted with respect to each other and shackle members projecting therefrom, the ends of said members having split portions bent in opposite directions for forming a firm joint at the ends of the said shackle members and means for preventing the movement of the said disks on their pivot points to prevent the unauthorized opening of the said shackle members.

In testimony whereof, I have hereunto set my hand, in presence of two witnesses.

CHARLES G. TAYLOR.
